UNITED STATES PATENT OFFICE.

WYATT M. INSKO, OF CARLISLE, KENTUCKY.

GRAIN-DOOR.

1,229,085.

Specification of Letters Patent.

Patented June 5, 1917.

Application filed November 11, 1914. Serial No. 871,606.

To all whom it may concern:

Be it known that I, WYATT M. INSKO, a citizen of the United States, residing at Carlisle, in the county of Nicholas and State of Kentucky, have invented certain new and useful Improvements in Grain-Doors; and I do hereby declare the following to be a full, clear, and exact description of the invention, such as will enable others skilled in the art to which it appertains to make and use the same.

My invention relates to grain doors and comprehends certain new and useful improvements in grain doors for railway cars of the type that are removable and comprise a number of hingedly connected door sections which may be folded.

The primary object of my invention is to provide a removable sectional grain door for railway cars that is provided with effective outlet means including a flexible and extensible discharge spout so arranged that the contents of the car may be discharged therethrough without necessitating removal of the door.

Another object is to provide a car door which consists of upper and lower sections that are hingedly connected with each other at a point near the center of the door, the upper section comprising a pair of hinged portions, the upper being arranged to swing inwardly so that when desired a person may get into the car without necessitating the removal of the entire door.

Another object is to generally improve grain car doors so as to render them more practical, reliable and efficient in operation and capable of being assembled and disassembled without materially increasing the cost of manufacture thereof.

The above and additional objects are accomplished by such means as are illustrated in the accompanying drawings, described in the following specification and then more particularly pointed out in the claim.

With reference to the drawings, wherein I have illustrated the preferred embodiment of my invention as it is reduced to practice, and throughout the several views of which similar reference numerals designate corresponding parts—

Figure 1 is a fragmentary side elevation of a grain car showing my door attached and in closed position,

Fig. 2 is an inside elevation of the door;

Fig. 3 is a vertical sectional view taken on line 3—3 of Fig. 1,

Fig. 4 is a fragmentary perspective view of the door in folded position showing part of the door removed, and

Fig. 5 is a transverse sectional view on line 5—5 of Fig. 4.

Referring to the drawings by characters of reference, A designates as an entirety a car door frame and B my improved door mounted within the frame. The door B comprises lower and upper door sections 1 and 2 respectively that are hingedly connected with each other by specially constructed hinges 3 which are mounted upon the outer faces of the sections 1 and 2. Each of the hinges 3 comprises leaves 4 and 5. Rolled ears are carried upon the opposed ends of the leaves 4 and 5, said opposed ends being disposed in spaced relation to the meeting edges of the sections.

A link member 6 having ears on its end connects the leaves 4 and 5 with one another. Hinge pins 7 are inserted through the ears on the members 4, 5, and 6, said ears alining. It will thus be seen when the sections 1 and 2 are folded, they are held spaced apart for a distance, equal approximately to the length of the link member 6. This arrangement is for a purpose to be later more fully described.

The upper section 2 comprises upper and lower sections 8 and 9 respectively of the same size and which are hingedly connected with each other by suitable hinges 10 which are arranged upon the inner faces of the sections 8 and 9 so as to permit the upper section 8 to fold or swing inwardly relative to the car.

As a means for holding the upper section 8 or in fact the door securely within the frame, I provide an L-shaped bracket 11 to be secured upon the lower face of the upper horizontal bar 12 of the door frame A and having its one arm portion depending from said bar 12 and apertured to receive a bolt 13 carried by the upper section 8. The bolt 13 is inserted through said member 11 and a nut 14 is turned on the threaded end of the bolt.

I provide means for holding the sections 8 and 9 of the upper section 2 in comparatively rigid relation to one another which consists of a locking metallic strap 15 that is hinged as at 16 to the lower section 9 of

the upper section 2 and arranged to extend upwardly and engage the outer face of the upper section 8. The free end of the strap 15 is longitudinally slotted to receive a bolt 16^a inserted from the inside of the upper section 8 and having a nut 17 turned on its outer or threaded end. It will be seen that when the bolt 16^a is inserted through the slotted end of the strap 15 and the nut 17 turned to clamp the strap upon the outer face of the upper section 8, a comparatively rigid structure is provided.

Fixed upon the inner faces of the sections 1 and 9 are back strips 18 which are apertured and arranged to aline with apertures in the sections 1 and 9. Bolts 19 are carried by the vertical bars of the door frame A and have their threaded ends disposed beyond the outer faces of the bars of the frame A to which they are attached so that they may be inserted through the apertures in the sections 1 and 9 and back strips 18 as shown in Fig. 3 in the drawings. Nuts 20 are turned on the outer ends of the bolts 19 and securely hold the door B in position. To remove the door B as an entirety it is first necessary to remove the nut 14 attached to the upper section 8 from the bracket 11 and to remove the nut 20 from the bolt 19. When the door sections are folded as shown in Fig. 4 the back strips 18 are removed. Carried adjacent to the lower edge of said section 1 are bolts 21 which have their threaded ends disposed outwardly from the outer face of the section 1 and have mounted on said extended portions cylindrical spacing collars 22. The bolts 21 extend beyond the outer ends of the collars 22 sufficiently to be inserted through openings 23 formed in the upper section 2. This arrangement is had when the door is folded as shown in Fig. 4. Nuts 24 are turned on said bolts 21 after they are inserted through the apertures 23 as described. Thus it will be obvious that the door will be locked in folded position.

In the lower door section 1 at a point adjacent to its lower edge, I provide an outlet opening 25. Secured to the lower door section 1 and communicating with the discharge opening 25 is a flexible and extensible discharge spout 26 which is arranged to be disposed in an outwardly and downwardly curved position. This discharge spout 26 consists of a plurality of telescoping frustoconical rings 27, the innermost and smaller 28 of which being secured to a flat metal body or attaching plate 29 and alining with the opening formed in said plate 29.

Secured upon the outer face of the lower door section 1 is a base plate 30 having a circular opening 31 therein which alines or communicates with the opening 25. Rotatably mounted between the plates 29 and 30 is a disk valve 31^a provided with an open-

ing 32 therein arranged to aline with the opening in the plate 29 and the one 31. A bolt 33 is inserted through the door section 1, plate 30, aperture 34 in the center of the disk valve 31^a and plate 29. A nut 35 is turned upon the outer end of said bolt 33. The detaching plate 29 is provided adjacent to its upper edge with an arcuate slot 36. An operating handle 37 is carried by the disk valve 31^a adjacent to the periphery thereof and upon its forward face and is slidably mounted within the slot 36. By means of the handle 37 the disk valve 31^a may be rotated to bring the opening 32 into and out of registration with the discharge opening 25 and opening 31 in the plate 30.

As a means for locking the disk valve 30 in such position that the opening 32 will be out of registration with the opening 31 in the plate 30, I provide a locking plate 38 that is hinged as at 39 to the plate 29 at one end and at its other end is bifurcated as at 40 to receive the handle 37. The plates 29 and 30 are secured by bolts 41 that are inserted through the section 1^a and the plates 29 and 30 adjacent to the edges of the plates so as not to interfere with the disk valve 31^a upon rotation of said valve. Nuts are turned on said bolts 41 and are disposed upon the outer face of the door. 95

The door after being removed from the frame is folded into the position shown in Fig. 4 in the drawings and the bolts 21 extended through the openings 23 in the upper section 2 of the door. By means of the spacing collars 22 and connecting links or link plates 6 of the hinges 3, the sections 1 and 2 are spaced from one another sufficiently to accommodate the nozzle 26 therebetween, said nozzle being collapsed. Prior to the folding of the section 2 upon the section 1 the locking strap 15 is made fast as described with the upper section 8 of the door section 2.

It will be seen that a grain car equipped with my improved car door may be unloaded in a reliable and expeditious manner. I consider the flexible extensible discharge spout or nozzle and valve structure co-operating therewith the most essential part of my invention. 110

My improved door may be folded so as to take up little space and in such manner that injury to the discharge mechanism therefor is prevented. 120

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be re- 125 130

sorted to, when required, without sacrificing any of the advantages of my invention, as set forth.

What is claimed is:—

- 5 The combination with a car, having a door frame, and a grain door composed of upper and lower sections, the lower section being provided with a discharge opening, a plate mounted on the lower section of the
- 10 door in spaced relation with the opening, and having an opening registering with the discharge opening, hinges connecting the sections of the grain door, said hinges being provided with elongated intermediate leaves
- 15 spacing the upper section from the lower

section, when the said upper section is swung downwardly, and an outwardly projecting extensible spout composed of tubular sections telescopically arranged, one of the sections being fixed to the said plate and 20 the said sections collapsing to a size to permit the spout to be arranged in the space between the sections of the door.

In testimony whereof I affix my signature in presence of two witnesses.

WYATT M. INSKO.
